UNITED STATES PATENT OFFICE.

ALWILL URBAHN, OF BROOKLYN, NEW YORK, ASSIGNOR TO THE AMERICAN LOOP FABRIC COMPANY, OF SAME PLACE.

WOVEN FABRIC.

SPECIFICATION forming part of Letters Patent No. 474,883, dated May 17, 1892.

Application filed May 23, 1891. Serial No. 393,806. (Specimens.)

To all whom it may concern:

Be it known that I, ALWILL URBAHN, a resident of Brooklyn, county of Kings, and State of New York, have invented a new and useful Improvement in Woven Fabrics, of which the following is a full, clear, and exact description.

My invention relates to the improved construction of a fabric hereinafter clearly shown and described; and it consists in combining in a fabric an inlay-thread with certain warp and weft threads and figure-cords, all securely locked, as hereinafter more fully described.

The object of my invention is to construct a fabric the faces of which are formed by ornamental or other cord, which is securely locked in place by warp and weft threads, one side of which may be one color and quality while the opposite side may be of another color and quality.

My invention is illustrated by the accompanying drawings, in which—

Figure 1 is a diagrammatical enlarged face view of the fabric. Fig. 2 is a similar bottom or reverse view of said fabric. Fig. 3 is a similar cross-section on the line 3 3, Fig. 1. Fig. 4 is a similar longitudinal section on the line 4 4, Fig. 1. Fig. 5 is a cross-section of part of a loom on which the fabric can be produced.

j, j^2 represent the ornamental or other cords which form the faces of the fabric.

a, b are the main warp-threads, which interlock in the manner hereinafter described and hold the cords j, j^2 into the fabric.

c is an intermediate warp-thread, which passes between the cords j, j^2 and serves to make the fabric even.

s, s are weft-threads around which the threads a, b turn and by which they are held.

From the diagram Fig. 4 it will be seen that the upper warp-thread a first goes around the upper cord j , then down under the weft-thread s , again up over the next cord j , again down under the weft-thread s , up over the third cord j , and so on. The lower warp-

thread b goes around the lower cord j^2 , up around the thread s , down around the next cord j^2 , and so on. The warp-thread c is above the weft-threads s, s , as shown. By this method it will be seen that a fabric having its opposite sides differently colored may be readily made by having one cord j of one desired color and quality and the other cord j^2 of another desired color and quality. In the finished fabric the embedded warp-threads a, b and the threads s and c are practically invisible. The warp-threads a are agitated sidewise from one side to the other to give them a zigzag form in the fabric and place them alternately to the right and left of the warp c , as shown in Fig. 1, producing thereby a higher tension and a securer lock, the needle-heddle that carries the warp a entering, for example, on opposite sides of the thread c , as in Fig. 1. The warp-threads b may be agitated in like manner.

One mechanism by which I construct this fabric is shown and described in the application bearing Serial No. 393,383, filed by me on the 20th day of May, 1891. Fig. 5 gives one view of said mechanism, showing at A the bat-ten, at B the shuttle, at C the heddle for the warp a , at D the heddle for the warp b , at E the guide for the warp-thread c , at F and G the carriers for the cords j, j^2 , respectively, and at H a beam around which the finished fabric passes.

Having thus described my invention, what I claim is—

A fabric consisting of two main warp-threads a, b , an intermediate warp-thread c , face-cords j, j^2 , and the weft-thread s , the warp a being placed under the weft-thread s on opposite sides of the warp c alternately and being laid over the cords j and under the weft s , the warp b passing over the weft s and under the cords j^2 , all substantially as and for the purpose specified.

ALWILL URBAHN.
